UNITED STATES PATENT OFFICE

2,418,705

DRIVE OF RAYON SPINNING BOXES

Leslie Charles Goodwin and Charles Tinsley,
Parkside Mills, Golborne, near Warrington,
England, assignors to Harben's (Viscose Silk
Manufacturers) Limited, Golborne, near War-
rington, Lancashire, England, a company of
Great Britain

Application September 24, 1945, Serial No. 618,214
In Great Britain October 12, 1944

1 Claim. (Cl. 57—77)

1

This invention has for its object to provide an improved arrangement of the drive from the usual self contained motor unit to the spinning box which obviates the projection of air currents on to the spinning box which cause crystallisation in the yarn in the box and on the exterior of the box of the spinning bath liquor. The improved arrangement also obviates the passage of such liquor to the exterior of the motor unit.

The invention consists in a driving arrangement of a rayon spinning box comprising a motor unit, a spindle driven by said unit, a spinning box upon and driven by said spindle, and a spinning box chamber around said box, the aforesaid spindle passing through a hole in the base of the chamber, characterised in this, that an imperforate annular frame upon the top of the motor unit extends through an upstanding or upwardly projecting lip around the hole in the base of the chamber, and a flexible ring attached to said frame extends over the top of said lip, a thrower upon the motor spindle projecting over the top of the annular frame to prevent liquor passing into the frame and on to the motor unit.

Referring to the accompanying explanatory drawings:

Figures 1 and 2 are sectional elevations showing two spinning box driving arrangements in accordance with this invention.

We provide an imperforate annular frame *a* upon the top of the motor driven spindle unit *b*, such frame projecting through the hole *c*, formed in the base of the spinning box chamber *d* and in the base of the spinning box chamber *d* and we secure the centre portion of a flexible or rubber ring *e* to the top of such frame *a*, the outer portion of such ring extending over the upwardly projecting lip *f* around the hole before referred to in the base of the spinning box chamber so as to prevent the passage of air or liquid around such frame.

The spindle *g* of the motor unit projects above the annular frame *a*, where it has a mushroom shaped head or thrower *h* thereon beneath the disc *i* upon which the bottom of the spinning box *j* rests and by which it is driven in the usual manner. The mushroom shaped head or thrower projects over the top of the annular frame so as to prevent liquor passing into the frame and on to the motor unit from the spinning box above. No air passes through the annular frame

so that rotation of the spinning box cannot cause any air circulation from below, such as would cause crystallisation of the spinning bath liquor on the exterior of the box or in the yarn in the box. The annular frame *a* may be integral with instead of attached to the top of the motor unit.

In Figure 2, an imperforate annular frame *k* of conical shape is used, to which is secured the centre portion of a flexible ring *l* having a beaded or thickened edge *m*. The upwardly projecting lip *n* around the hole in the base of the spinning box chamber also has a beaded or thickened edge *o*, over which the edge *m* passes in order to give a good seal between the ring *l* and the lip *n*.

What we claim is:

A driving arrangement for a rayon spinning box, comprising a motor unit, a spindle driven by said unit, a spinning box upon and driven by said spindle, a spinning box chamber around said box, 15 an imperforate annular frame upon the top of the motor unit, the base of the spinning box chamber being apertured to allow the spindle and the annular frame surrounding the spindle to pass through, an upwardly projecting lip around the aperture in the base of the chamber, a flexible ring attached to said frame and extending over the top of said lip, and a thrower upon the spindle beneath the spinning box, projecting over the top of the annular frame and spaced from the flexible ring, to prevent liquor passing into the frame and on to the motor unit.

LESLIE CHARLES GOODWIN.
CHARLES TINSLEY.
